Set of Concrete breakwater blocks, available in website.com, announced Year 2019 [online], [site visited Jan. 30, 2024], Internet URL: <https://www.artstation.com/artwork/LAw20> (Year: 2019).*

(Continued)

Primary Examiner — Sandra Snapp*Assistant Examiner* — Jasmine L. Coleman(57) **CLAIM**

The ornamental design for a block for breakwaters as shown and described.

DESCRIPTION

Figure 1.1 : Perspective view of a block for breakwaters showing my new design;

Figure 1.2 : Front elevation view thereof, the rear elevation view being a mirror image thereof;

Figure 1.3 : Left elevation view thereof, the right elevation view being a mirror image thereof; and

Figure 1.4: Top plan view thereof, the bottom plan view being a mirror image thereof.

The broken lines in the drawings show portions of the block that form no part of the claimed design.
